UNITED STATES PATENT OFFICE.

JOHN HOFFER, OF BAXTER, WEST VIRGINIA.

SAFETY-STOP FOR ELEVATORS.

Specification of Letters Patent. Patented Oct. 17, 1911.

1,005,837.

Application filed February 10, 1911. Serial No. 607,799.

To all whom it may concern:

Be it known that I, JOHN HOFFER, residing at Baxter, in the county of Marion and State of West Virginia, a subject of the Emperor of Austria-Hungary, have invented or discovered certain new and useful Improvements in Safety-Stops for Elevators, of which improvements the following is a specification.

10 Elevator-cars that are used primarily for handling articles of commerce, for example such as operate in mining shafts, usually consist of a platform, either rigidly or movably sustained within a frame, which frame 15 is guided by vertical posts in the movement up and down the shaft. To the end that the car may not fall, in case the cable breaks when the car is in elevated position, the car has been provided with suitable cam-shaped 20 blocks, with indented surfaces, to engage the guide-posts as soon as the cable becomes slack, due to its rupture or any other cause. As heretofore constructed, cam-blocks of the 25 character described have been operated by springs. In the operation of such elevators, the guide-posts, which are usually made of wood, become worn, and thereby considerable play is allowed between the posts and the guide-blocks of the frame of the car, 30 which play is of itself undesirable in the normal operation of the elevator and may lend itself to serious consequences by permitting the cam-blocks to turn over completely in case the cable should break.

35 My invention relates to improvements in elevators of the character described and the object of my invention is to provide a compensation for the wearing of the guide-post and in so doing to provide a safety device 40 for elevator cars that will not be dependent upon the uncertain action of a spring.

While my invention finds application in any elevator wherein the above conditions arise I choose to describe it in its application to an elevator of the type usually used 45 in a mine shaft.

In the accompanying drawing, which forms part of this specification, Figure 1 is an elevation of a freight elevator embodying my invention; Fig. 2 is a side view of the same; and Fig. 3 is a sectional view taken on the line III—III, Fig. 2.

In the several figures like numerals refer to like parts.

The elevator car shown herein conveniently consists of two major parts, a platform and a frame, which parts move simultaneously in the normal operation of the car, but are movable with reference to each other in case an accident causes the cable to slacken. Of these parts, the platform 1 is conveniently provided with sides 2. Vertical sustaining members 3, 3 are secured to each side, and, at their upper ends, the said sustaining members are yoked together by 65 a suitable block 4, which may be suspended from the cable 5 by a bolt 6. The said block 4 is inclosed loosely within the upper portion of the frame, which upper portion conveniently consists of a horizontal channel 70 7 and vertical plates 8. To the said plates 8 I secure guide blocks, suitable in form and in construction, to the particular type of guide-posts used. As usually constructed the guide-posts 9 are made of wood and are 75 rectangular in cross-section. The guide-blocks for such guide-posts I preferably make of pairs of angles 10 and 10^a, suitably secured to the vertical plates 8, as by lug angles 11, and I arrange the blocks one 80 on each side of a guide post. To each angle 10 I suitably secure an adjusting-bar 12, to the end that, as the guide blocks wear away, not only the loose play may be taken up, but also a slight frictional contact may 85 be maintained. Preferably, the said adjusting-bars 12 are made of steel flats, suitably provided with smooth holes, which extend partly through the flats, and into which the screw-threaded bolts 13 extend. It will 90 be understood that the angles 10 have screw-threaded holes, which register with the smooth holes of the adjusting-bars, and that a turning of the bolts 13 may be effective 95 to move the adjusting-bars away from the angles 10, thereby diminishing the width of the passageways for the guide-posts.

The pair of guide blocks 10 and 10^a may be connected to each other at their lower ends, as by plates 14, suitably provided with 100 bearings for the rotatable shafts 15 and 15^a, on which shafts I secure indented cam-shaped blocks 16, preferably placing one on each end of each shaft. The shafts are suit-

ably connected, as by levers and links, to the platform, to the end that, when the elevator is running normally, the indented cams 16 will be held away from engagement 5 with the guide-posts, but that, when the platform has moved downward a little in advance of the frame (as it will, should the rope 5 break) the said cams will be brought into engagement with the guide-posts, and 10 will thereby stop the car's descent, in a manner that is well known by those skilled in the art.

That the platform will drop in advance of the frame, in case the cable should break 15 or slacken, will be understood from the fact that the guide-blocks are adjusted to constantly have a frictional engagement with the guide-posts, which frictional engagement will retard the descent of the frame 20 sufficiently to allow the platform to fall in advance of the frame and thereby bring the car to a stand-still as heretofore explained.

It will be observed of my invention that a safety stop is accomplished without employing 25 a spring, the reliability of which has been found by experience to be uncertain. Furthermore, it will be understood that the operation of one of the shafts 15 or 15^a, with its cam-block 16, will be sufficient to stop the 30 car, and it will be observed that the shaft 15^a with the cams 16, being arranged to engage the posts 9 on the sides opposite the adjusting-bars 12, will remain, whatever be the degree of adjustment, in fixed relative 35 position to the said guide-posts, so that it will be impossible for the said cams to turn completely over in consequence of the wearing away of the substance of the posts, and thereby permit the car to drop, an occurrence 40 that would remain possible in case the adjustment were taken up equally on each side of the posts or in case the adjustments were not taken up at all.

I do not wish to limit myself to the details 45 of construction shown and described

herein, for obviously many changes may be made by those skilled in the art without departing from the spirit of my invention.

I claim as my invention:

1. In an elevator, the combination of 50 guide posts and a car, said car consisting of a frame and a platform, which members move in unison in the normal operation of the car, but which may move relatively to each other when the car is unsupported, a 55 safety-cam rotatably secured to one of said car-members and having operative connection to the other of said car-members, an adjusting bar secured to the safety-cam-carrying car-member and maintaining constant friction with the elevator guides during the operation of the car, said bar being operative (in case the car-supporting member gives away) to retard the downward movement of the safety-cam-carrying car- 60 member relative to the said other car-member, said relative downward movements of the car members being operative to set the said safety cams, substantially as described.

2. In an elevator, the combination of 70 guide-posts and a car, said car comprising a suspended platform and a frame movably sustained by said platform, said frame provided with adjustable passageways maintaining constant friction with said guide- 75 posts, a shaft rotatably secured to said frame and provided with a safety-cam, an arm rigidly secured to said shaft and having linked connection to said platform, said friction passageways being operative 80 to retard the downward movement of the frame to accomplish a setting of the safety-cams in case of accident to the car-supporting member, substantially as described.

In testimony whereof I have hereunto set 85 my hand.
